United States Patent Office.

GEORGE SMITH, OF PROVIDENCE, RHODE ISLAND.

Letters Patent No. 86,184, dated January 26, 1869.

IMPROVEMENT IN FARM-GATES.

The Schedule referred to in these Letters Patent and making part of the same.

To all whom it may concern:

Be it known that I, GEORGE SMITH, of Providence, in the county of Providence, and State of Rhode Island, have invented a new and useful Improvement in Farm-Gates; and I do hereby declare that the following is a full, clear, and exact description thereof, reference being had to the accompanying drawings, making a part of this specification, in which—

Figure 1 is a perspective view of a picket-gate, having my improvements applied to it.

Figure 2 is a perspective view of a rail-gate, having my improvement applied to it.

Figure 3 is a side elevation of the rail-gate, showing, by the aid of lines, one end, partially elevated.

Figure 4 is a top view of the rail-gate, swung partially open.

Similar letters of reference indicate corresponding parts in the several figures.

The nature of my invention consists in the combination, with a gate which is hung on hinges, and swings horizontally, and vibrates vertically, of a weight for balancing it, as will be hereinafter described, this combination being an improvement on gates which swing horizontally and vibrate vertically, but are not balanced; also, an improvement on balanced gates which are not suspended on hinges, but are capable of swinging horizontally and vibrating vertically.

To enable others skilled in the art to understand my invention, I will describe its construction and operation.

In the accompanying drawings, I have represented my invention applied to two kinds of gates, namely, the picket-gate, shown in fig. 1, and the rail-gate, shown in figs. 2, 3, and 4.

In figs. 2, 3, and 4, A represents a hollow post or box-post, which is somewhat higher than the height of the gate, and which is provided, near its upper end, with a grooved sheave, b, over which a rope or chain, a, passes, which is attached to the gate, as will be hereinafter explained, and provided with a balancing-weight, B, which is designed to balance or nearly balance the weight of the free end of the gate.

This gate consists of horizontal rails, F, which are pivoted, in a suitable manner, between the vertical pickets, G E, so that the free end of the gate, or that end nearest the latching-post C, can be vibrated vertically.

To the bottom rail F of the gate, near the pickets E, two bars a' a' are pivoted at c, on opposite sides of the gate, and connected together at c', their upper ends, and by these ends attached to the rope or chain a of the balancing-weight B, as clearly shown.

The upper ends of the two bars a' are free to vibrate, so as to allow the gate to be vibrated vertically.

By this arrangement, it will be seen that the balancing-weight will not only prevent the gate from sagging, but it will also assist in raising the free end

of the gate in the act of opening the gate, by giving its free end a vertical movement.

It will also be seen that the weight of the free end of the gate will be sustained at the point c by the balancing-weight B, acting through the medium of the rope or chain a and the pivoted bars a'.

This gate is connected to the hollow post A by means of hinges d d, constructed in any suitable, well-known manner, which will allow the gate to swing horizontally when released from the post C.

This gate is fastened, when shut, by means of extensions of the top and bottom rails, which are received in forked ends e e' of the post C, as shown in the drawings, and also by the nose of a latch, D.

The forked ends e e' prevent lateral displacement of the free end of the gate, and the latch D, which may be made in the manner shown, or in any other suitable manner, will prevent the free end of the gate from casually rising.

Thus it will be seen that, in order to open my gate, the latch D must be forced back, and the free end of the gate lifted until the extensions of the top and bottom rails will escape horizontally from the notches e e' in post C.

At a suitable point on one of the pickets or upright bars, E, a hook, f, is pivoted, which is fastened to the eye f, on post f, when the gate is raised, as indicated in red lines, fig. 3.

This will allow small animals to pass under the gate, but will prevent horses and other large animals from passing through the gate-opening.

The picket shown in fig. 1 is constructed substantially in the manner described for the rail-gate. In this picket-gate the rope or chain g is passed through the upper rail, and carried off to a point near the pickets or bars E, and attached to the lower rail, thereby dispensing with the pivoted bars a' a', shown in figs. 2, 3, and 4.

One of the great advantages of my improved gate over all other gates is, that it can be readily lifted over snow-banks and swing open; another advantage is, that it cannot sag; and another advantage is, that it can be constructed and made to work well by a person of ordinary mechanical skill.

Having described my invention,

What I claim as new, and desire to secure by Letters Patent, is—

1. The combination of a weight for balancing, with a vertically-vibrating gate, hung on hinges, which are applied substantially as described.

2. The weight B and rope or chain, applied as shown, in combination with a gate which swings laterally, and vibrates vertically, substantially as described.

GEORGE SMITH.
